UNITED STATES PATENT OFFICE.

SIDNEY C. WILSON, OF PENN YAN, NEW YORK, ASSIGNOR TO WILSON PROCESS, INCORPORATED, OF ROCHESTER, NEW YORK, A CORPORATION OF NEW YORK.

LAST.

Application filed April 25, 1918. Serial No. 230,635.

To all whom it may concern:

Be it known that I, SIDNEY C. WILSON, a citizen of the United States, and resident of Penn Yan, in the county of Yates and 5 State of New York, have invented an Improvement in Lasts, of which the following description, in connection with the accompanying drawings, is a specification, like letters on the drawings representing like 10 parts.

Lasts are used in the manufacture of shoes to support the shoe parts in the proper relationship to each other while they are being secured together and to give shape 15 and character to the shoe. The present invention aims to devise an improved form of last which will perform not only the functions of the lasts heretofore used but will also perform certain additional functions 20 that facilitate the shoe manufacturing steps. Stated more specifically the invention is directed to the provision in a last of means for protecting certain parts of a shoe supported thereon with a view to reducing the 25 liability of injury to these parts during the various steps in the process of manufacture of the shoe. It is also a particular object of this invention to provide a last with means for retaining certain portions of the 30 shoe supported thereon in the proper temper for the manufacturing operations on said parts, the term "temper" being used in the trade sense to designate that condition in which the stock contains sufficient moisture 35 or some other softening agent to keep it in a soft and pliable condition. These objects and the manner in which it is proposed to accomplish them will be readily understood from a detailed description of 40 one embodiment of the invention and the novel features will be particularly pointed out in the appended claims.

Referring now to the drawings,

Fig. 1 is a side elevation of a last constructed in accordance with the invention;

Fig. 2 is a plan view of the bottom of the last; and

Fig. 3 is a cross sectional view on the line 3—3, Fig. 1.

The drawings show a very common commercial type of divided last comprising a forepart 2 and a heel part 4 joined together by links that permit the relative movement of the heel and foreparts from an extended 55 position in which they are shown in the

drawings to a collapsed or broken condition, and vice versa. The bottom or sole supporting face of the last is provided at the heel seat with the usual anvil plate 6 and in front of the heel seat with a yielding moisture retaining covering 8, preferably set into a recess formed in the central portion of the last bottom, and surrounded by a marginal tack receiving portion 10. The body of the last is made of some relatively rigid material, usually wood, and the insert 8 should be made of some yielding, fibrous material, capable of retaining moisture, or any other tempering agent, herein referred to as moisture. Preferably the covering 8 is made 60 of felt. For some uses, as for instance in manufacturing welt or turn shoes, the felt insert 8 should be of such a thickness that it will lie substantially flush with or will project slightly beyond the surface of the 65 tack receiving portion 10 but in the construction shown, which is intended primarily for the manufacture of McKay shoes, the sole supporting surface of the felt piece 8 lies slightly below the face of the margin 10. 70

This construction of last is of particular utility in manufacturing shoes of the type and according to the process disclosed in my applications Serial No. 230,634, filed April 25, 1918, and Serial No. 230,633, filed April 25, 1918, respectively, in which the insole is channeled on its inner surface to receive the stitches that unite the insole, upper, and outsole. Such an insole is prepared before being attached to the last by cutting the channel to receive the inseam stitches, turning back the channel flap in readiness for the stitching operation, and then coating this flap with cement so that after the stitching operation has been completed the flap can be at once turned down over the stitches and secured in this position without the necessity for then performing the flap cementing operation which could be done only with great difficulty after the stitching operation has been performed. The insole is in temper at the time that it is prepared for assembling on the last and it is desirable to retain the insole in this condition during the making operations in order 80 to prevent injury to the channel flap, which might be broken if it dried out and became brittle, to maintain the cement in a tacky and adhesive condition and to keep the insole in condition for the stitching operation. 85

60 65 70 75 80 85 90 95 100 105 110

In manufacturing shoes on lasts of the types now commonly used it is generally necessary to re-temper the soles before the stitching operation is performed; but by using a last 5 of the type herein shown and described the necessity for a second tempering is avoided since, if the felt covering is moistened thoroughly before the shoe is assembled, it will retain an ample supply of moisture to keep 10 the channel flap, and the insole in temper during the entire time that the shoe is on the last. Consequently when the shoe is removed from the last for the stitching operation the sole will be found in the proper 15 condition for this process, and the channel flap also will be properly tempered and in the required tacky condition to be turned down over the stitches immediately after the stitching operation has been completed. 20 The member 8 also acts as a cushion for the channel flap while the various making operations are being performed on the shoe and materially reduces the liability of breaking the flap. 25 A last of the type provided by this invention may also be used to advantage in the manufacture of other types of shoes than that above referred to, particularly in the manufacture of welts and turns, the moisture 30 retaining member operating to maintain the insole of the welt shoe or the sole of the turn shoe in temper while the making operations are being performed on them. If the turn shoe is channelled on its outer or tread 35 face the last will protect the channel flap in the same way that it protects the channel flap of the insole of the shoe above described. The fact that the felt covering 8 supplies moisture to the inner face of the 40 sole will materially prolong the period within which the sole will be retained in temper and will, in a large percentage of cases, avoid the necessity for re-tempering the channel flap or lip on the outer surface of the sole on 45 the last.

The margin 10 provided around the felt covering 8 affords ample space for the driving of the lasting tacks in manufacturing shoes of the welt, turn, or the peculiar Mc- 50 Kay type above described. If it were desired to manufacture the usual type of Mc-Kay shoe on this last, it is obvious that the margin 10 would then be provided with the

usual anvil plate against which the lasting tacks could be clinched. 55

While the invention has been herein shown as applied to a last of the divided type, it is obvious that it is equally applicable to a solid or block last and it will also be evident that if it should prove desirable 60 to retain in temper some other portion of the shoe than that specifically referred to it would merely be necessary to use a moisture retaining means, such as that indicated at 65 8, upon the part of the last which supports that particular portion of the shoe.

What is claimed as new, is:

1. A last having a sole supporting face comprising a marginal tack receiving portion and a moisture retaining portion adjacent to said tack receiving portion. 70

2. A last having a felt insert set into the central portion of the sole supporting face of the last in front of the heel seat, said face having a tack receiving margin around said 75 felt insert.

3. A last for boots and shoes having a rigid marginal portion on the last bottom raised substantially above the central portion of the last bottom and constituting a 80 marginal surface cooperating with the lasting of the shoe thereon, in combination with a cushioning insert set into the central portion of the last bottom confined by said raised marginal part and constituting moisture retaining means. 85

4. A last for use in manufacture of boots and shoes, having the last bottom in two planes, the inner central portion of the fore-part and shank being in a plane recessed 90 from that of the marginal portion of the last bottom above the plane of said inner recessed portion, and a filling for said recessed portion of cushioning material adapted as a moisture retaining means, said cushioning material substantially filling the central recess of the last, and constituting a 95 protecting housing for the channel flap on an insole during the lasting process.

In testimony whereof, I have signed my 100 name to this specification, in the presence of two subscribing witnesses.

SIDNEY C. WILSON.
